Robert M. Barr, Attorney

UNITED STATES PATENT OFFICE.

LEVI T. EDWARDS, OF PENFIELD, PENNSYLVANIA.

AIR-LIFT PUMP.

1,276,506.

Specification of Letters Patent. Patented Aug. 20, 1918.

Application filed June 5, 1918. Serial No. 238,315.

To all whom it may concern:

Be it known that I, LEVI T. EDWARDS, a citizen of the United States, and a resident of Penfield, Delaware county, State of Pennsylvania, have invented a certain new and useful Improvement in Air-Lift Pumps, of which the following is a specification.

Some of the objects of the present invention are to provide in an air lift pump means for reducing the friction of the moving column of water at the inlet end of the eduction pipe; to provide means for intimately mixing the compressed air with the water to prevent the formation of air pockets; to provide means for promoting the uniform flow of the body of lifted water; to provide means for maintaining the discharge orifices of the air nozzles clean and free from deposits; and to provide other improvements as will hereinafter appear.

In the accompanying drawings Figure 1 represents a sectional elevation of one form of foot piece for air lift pumps embodying the present invention; Fig. 2 represents a plan of one unit of the foot piece; Fig. 3 represents a side elevation of one form of foot piece embodying the present invention; Fig. 4 represents a section on line 4—4 of Fig. 1; and Fig. 5 represents a section on line 5—5 of Fig. 3.

Referring to the drawings one form of the present invention is shown as applied to an air lift having an eduction pipe 10 located in a well 11 with its lower or inlet end submerged as in the usual practice, and its upper end projecting out of the well 11 where it is suitably supported to discharge into a reservoir or tank (not shown).

For the purpose of lifting a column of water within the pipe 10 air under pressure is employed in the usual manner and delivered adjacent to and below the inlet of the eduction pipe 10 by means consisting, in the present instance, of three delivery pipes 12, which lead from above the ground level to the vicinity of the submerged inlet of the pipe 10. Each of the pipes 12 connects with a suitable source of compressed air by way of separate supply conduits 13 which are respectively controlled by a manually operable valve 14 and each has a T fitting 15 of the three way type for the purpose of providing a separate discharge section 16 for each of the said pipes 12, said sections being respectively controlled by hand valves 17.

In order to intimately mix the discharged

air with the water, the eduction pipe 10 has its submerged or inlet end joined to a foot-piece, one form of which is here shown as embodying an annular body 20 secured to the air delivery pipes 12 and having a seat 21 to receive and fit snugly about the inlet end of the eduction pipe 10. The bore 22 of the pipe 10, at its juncture with the body 20, is of the same diameter as the diameter of the juxtaposed end of a transverse opening 23 but this latter gradually increases in diameter to form a flaring inlet for directing the water and air into the eduction pipe 10. The delivery pipes 12 are respectively threaded into the body 20 and have communication with the respective passages 24 which in turn are connected to a plurality of depending pipes 25, 26 and 27, which serve to distribute the incoming compressed air, as will later be described. The pipe 25 is connected to the body 20 and has free communication with its passage 24 in order to receive an unrestricted supply of air for delivery to a ring nozzle 30 which is carried by a hollow rigid arm 31 secured to the pipe 25. The construction is such as to locate the ring nozzle 30 below and concentric with respect to the axis of the main body 20, while the diameter of the ring 30 is less than the diameter of the mouth of the inlet to the body 20. The pipes 26 and 27 also connect with the body 20 and communicate with the respective air receiving passages 24 and respectively have hollow arms 32 and 33 for rigidly supporting ring nozzles 34 and 35 which are arranged in superposed relation below the nozzle 30 and concentric with respect to the axis of the eduction pipe 10 as well as the nozzle 30. The diameter of the ring nozzle 34 which is next below the ring nozzle 30 is less than the diameter of the ring nozzle 30, and the diameter of the ring nozzle 35 is less than the diameter of the ring nozzle 34 and hence an upwardly moving column of water passes through three stages of nozzles of increasing diameter and all of which in addition are spaced sufficiently from each other to permit free circulation of water between the nozzles.

For the purpose of intimately mixing the discharged air with the water the several ring nozzles are each provided with an upper, outer series of discharge orifices 36 and a lower inner series of discharge orifices 37, the former series being angularly disposed to discharge the air upwardly in the general

direction of the inlet to the next adjacent ring nozzle and the latter series being angularly disposed to discharge the air downwardly and across the column of water moving upwardly through the ring opening. Thus the body of water on the respective courses denoted by arrows A will be thoroughly commingled with air while the body of water on the course of arrow B will also be intimately mixed. This construction prevents the formation of air pockets and promotes a uniform velocity to the moving column of water.

In order to reduce the friction and negative the presence of the ring nozzles the sectional shape of the hollow ring wall is substantially that of an ellipse with relatively sharp edges at the extremities of the long diameter. In view of the position of the ring nozzles the long diameter of the ellipse form is parallel to the axis of the rings and consequently the sharp edges 40 at the lower end divide the water with relatively little friction so that it flows freely upwardly and follows the easy curve of the ring section.

For the purpose of automatically cleaning and maintaining the orifices 36 and 37 free from dirt and sediment, scale or like deposits, each of the pipes 25, 26 and 27 is provided with a check valve 41 at its lower extremity, which is adapted to open downwardly; thus under normal operating conditions the air pressure maintains the water level in the pipes below the lowermost ring nozzle so that the air freely discharges in opposite directions, both outwardly and inwardly, from the respective nozzles and mixes with the moving column of water. Should it be desirable, however, to blow out the orifices 36 and 37 for cleaning purposes the compressed air supply from one of the ring nozzles, say for example 34, is cut off by closing the valve 14, which admits air to the pipe 26, and at the same time opening the valve 17 which places the pipe 26 in communication with the atmosphere. This causes a sudden and considerable drop in pressure in the pipe 26 and the surrounding water rushes through the orifices 36 and 37 of the ring nozzle 34 in a direction counter to its usual course, thus blowing out any of the collected dirt or sediment. The check valve 41 for pipe 26 closes under this action thereby making the aforesaid orifices 36 and 37 of the ring nozzle 34 the only inlet for the water to pipe 26 and consequently a thorough flushing and cleaning takes place. In connection with this reversal of flowing through the orifices, it should be noted that the cleansing operation may selectively take place and any one of the ring nozzles cleaned or if desired all may be cleaned at once, though this latter is not generally advisable as more effective results may be obtained by maintaining several nozzles under com-

pressed air, while one is cut off and subject to atmospheric pressure for cleaning purposes.

For the purpose of finally mixing air with the column of moving water as it enters the eduction pipe 10 it is preferable to form an annular chamber 42 in the ring 20 and which has communication with the passage 24 by a port 43 so that air under pressure enters by way of one of the pipes 12, has free access to the chamber 42 and is discharged therefrom by way of the series of downwardly directed orifices 44. The air therefore is discharged from a plurality of points on the circumference of the ring passage and is directed transversely of the water column whereby it becomes intimately mixed in the required manner as will be understood.

It will now be apparent by the foregoing described apparatus that the column of water set in motion by and moving under the influence of the discharged compressed air is directed efficiently to the inlet of the eduction pipe without meeting obstructions or abrupt bends or turns to create friction. Further at each entrance to the nozzles and to the inlet of the eduction pipe the water is subjected to a plurality of cross currents of air which thus become mixed in a complete and effective manner to prevent the formation of air pockets which reduce the velocity of the water and impair the delivery.

While I have in the present instance disclosed but one form in which this invention may be embodied, it is to be understood that the invention is not limited to any particular construction but might be embodied in various forms without departing from the spirit of the invention or the scope of the appended claims.

Having thus described my invention, I claim and desire to protect by Letters Patent of the United States:

1. In an air lift pump, the combination of an eduction pipe, a plurality of nozzles supported below said pipe, each nozzle having a series of discharge orifices, and means for delivering air to said nozzles.

2. In an air lift pump, the combination of an eduction pipe, a plurality of superposed nozzles supported below said pipe and of different diameters, each nozzle having a series of discharge orifices, and means for delivering air to said nozzles.

3. In an air lift pump, the combination of an eduction pipe, a plurality of superposed nozzles supported below said pipe, each nozzle consisting of a ring having two series of orifices, one series discharging in one direction and the other series in another direction, and means for delivering air to said nozzles.

4. In an air lift pump, the combination of an eduction pipe, a plurality of superposed

nozzles of ring form decreasing respectively in diameter from said pipe, each nozzle having a substantially circular series of orifices arranged to discharge toward the next adjacent nozzle, means for delivering compressed air to said nozzles, and means to support said nozzles below said eduction pipe.

5. In an air lift pump, the combination of an eduction pipe, a plurality of superposed nozzles of ring form decreasing respectively in diameter from said pipe, each nozzle having two series of orifices arranged to discharge in opposite directions, means for delivering compressed air to said nozzles, and means to support said nozzles below said eduction pipe.

6. In an air lift pump, the combination of an eduction pipe, a plurality of superposed nozzles of ring form supported below said eduction pipe, each nozzle having two series of orifices, one series being arranged to discharge away from the axis of the nozzle and the other series being arranged to discharge toward the axis of the nozzle, and means to deliver compressed air to all of said nozzles.

7. In an air lift pump, the combination of an eduction pipe, a plurality of superposed nozzles of ring form supported below said eduction pipe, each nozzle having two series of orifices one series being arranged to discharge away from the axis of the nozzle and the other series being arranged to discharge toward the axis of the nozzle, means to deliver compressed air to all of said nozzles, and manually controlled means for causing a reversal of the direction of fluid flow through said orifices whereby said nozzles are flushed and cleaned.

8. A foot piece for an air lift pump consisting of an annular body, a plurality of ring nozzles of different diameters, and means to support said nozzles in axial alinement with said body.

9. A foot piece for an air lift pump, consisting of an annular body having a chamber therein and a plurality of orifices, a plurality of ring nozzles in axial alinement with said body, and means for supplying compressed air to said chamber and to said nozzles.

10. A foot piece for an air lift pump consisting of a plurality of annular nozzles, each having a series of discharge orifices normally submerged, means to introduce air under pressure to said nozzles to be discharged through said orifices, and means to cause a reversal of the direction of fluid flow through said orifices whereby water enters said nozzles and said orifices are flushed and cleaned.

11. A foot piece for an air lift pump consisting of a plurality of submerged nozzles, means to introduce air under pressure to said nozzles to be discharged outwardly into the body of water, and selective means for causing a reversal of the direction of fluid flow through any nozzle whereby water enters the selected nozzle for cleaning purposes.

12. A foot piece for an air lift pump consisting of a plurality of submerged nozzles arranged in superposed relation, independent means for supplying each nozzle with air under pressure, and separate control means for the respective supplying means.

In testimony whereof I have hereunto set my hand this 13th day of May, 1918.

L. T. EDWARDS.
